UNITED STATES PATENT OFFICE.

ABRAM C. MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

SMOKE-CONSUMING FURNACE.

Application filed September 15, 1920. Serial No. 410,510.

To all whom it may concern:

Be it known that I, ABRAM C. MOTT, Jr., a citizen of the United States, residing in Philadelphia, Pennsylvania, have invented 5 certain Improvements in Smoke-Consuming Furnaces, of which the following is a specification.

My invention relates to certain improvements in smoke consuming furnaces of the 10 type illustrated in the patent granted to me on the 22nd day of March, 1921, No. 1,372,534.

One object of the present invention is to improve the construction of the furnace 15 mentioned above and to make the secondary combustion chamber in sections of substantially the same width as the sections of the boiler to which the invention is applied.

A further object of the invention is to 20 improve the detail construction of the combustion chamber and to arrange it so that it can be applied either to a horizontal boiler or to a vertical boiler.

In the accompanying drawings:

25 Fig. 1 is a side elevation illustrating my improved smoke consuming furnace;

Fig. 2 is a rear view;

Fig. 3 is a sectional view on the line 3—3, Fig. 2;

30 Fig. 4 is a sectional plan view of the rear of the furnace on the line 4—4, Fig. 3;

Fig. 5 is a sectional view illustrating a detail of the invention on the line 5—5, Fig. 3;

Fig. 6 is a sectional view on the line 6—6, 35 Fig. 2;

Fig. 7 is a perspective view of one of the secondary combustion chambers;

Fig. 8 is a vertical sectional view on the line 8—8, Fig. 9, illustrating a modification 40 of the invention as applied to a vertical boiler; and

Fig. 9 is a sectional view on the line 9—9, Fig. 8.

Referring to the drawings, 1 is the main 45 portion of the smoke consuming boiler furnace. 2 are the boiler sections which are coupled together side by side and secured in the ordinary manner. 3 is the base on which the sections rest. In this base is the 50 grate and below the grate is the ash pit. 4 is the front of the furnace having a feed door 5 and at the front of the ash pit section 3 is the ash pit door 6. Each section of the boiler, in the present instance, is made 55 with an overhanging portion 7 and a back

leg 8. In the overhanging section are the flues 9 and 10, one-half of a flue being in each section so that when the sections are assembled a complete flue is formed. In the bottom of the legs of each section 8 is an offset portion forming a mud drum 11.

At the mud drum of each section is an opening 12. The openings of one section are coupled to the openings of another section. At the upper end is an opening 13 forming a connection between the upper ends of the boiler sections so that water and steam circulate freely through all of the sections. The portion 7 of each section overhangs the primary combustion chamber 14, 70 this portion has a thin depending section 15 provided with hollow ribs 16 arranged so as to allow the products of combustion to heat the water within the sections more readily.

The above construction is common in this type of boiler but the combustion chamber usually connects directly with the lower flues 9 at the rear.

Located at the back of the portion 1 of 80 the furnace is a series of secondary combustion chambers 17, each chamber is of substantially the same width as the boiler sections 2. These sections overlap the joints of the boiler sections, as clearly shown in 85 the drawings. Each chamber 17 is made of cast metal, and has flue openings 21 and 22. The opening 21 communicates with a flue opening 23 in the boiler sections, as clearly shown in Fig. 3, while the opening 22 communicates with the flue 9, as shown in said figure, so that the products of combustion pass from the primary combustion chamber through the flues 23 and openings 21 into the secondary combustion chambers 17, and 95 from the secondary combustion chambers through the openings 22 into the flues 9.

Each casing 33 is recessed at 18 at the underside, and lugs 19 on the boiler project into these recesses and support the sections, 100 a rod 26 extends back of the lugs and hooked bolt 25 engage the rod and extend through projecting lugs 24 on the section 17. At the upper end of each section 17 is a lug 27 through which passes a bolt 28 having a head 105 resting in a recess 29 in the boiler section, as clearly shown in Fig. 3.

30 is a lining of non-conducting material extending at the back and at the top and bottom of the sections 17 of the secondary 110

- combustion chamber. This lining is enclosed in the top casing 31, back casing 32, and bottom casing 33. Each casing has lugs through which pass bolts 34, which hold the casings together. Each section 17 has an inclined slot 35 at the upper end and a horizontal slot 36 at the lower end, formed by cutting a saw kerf in the back of each section as shown in Fig. 7. These kerfs 5 form air passages, which permit the admission of air to the secondary combustion chamber. The upper passage 35 communicates with a passage 37 formed in the outer casing 32 and the lower passage 36 communicates with a passage 38, also formed in the back casing 32, as clearly shown in Fig. 3. The slots 37 and 38 extend through the end casings 43, as well as through the back casings 32. Between the end casings and 10 the sections 17 is a non-conducting lining 30^a. The end casings are secured to the back casings by bolts 44, which extend through lugs on the said parts.
- 39 is a series of vertical rods having heads 15 counter-sunk in the bottom casings 33 and having nuts at the upper end bearing upon the upper plate 31. These rods extend between the sections and tie them together vertically.
- 40 is a flue section mounted above all of 20 the sections 17 and the front of this section rests upon the boiler section 2 and has a plate 41 provided with a flue opening 42. This flue section 40 receives the products of 25 combustion from the series of flues 10 and directs them to the opening 42, which communicates with the flue leading to the chimney, as shown clearly in Fig. 2. While the primary combustion chamber is a single 30 chamber, the secondary combustion chamber consists of a series of independent chambers and there is a single flue 23 communicating with the lower portion of each section, and a flue 9 communicating with the upper portion 35 of each section.
- In a furnace, built as above described, the 35 products of combustion, as they are partially burned in the primary combustion chamber, pass through the flues 23 into the individual secondary combustion chambers 17 and, as 40 they pass through these chambers, air is admitted at the lower portion of the chamber through the slots 36 and at the upper end through the slots 35 so as to add sufficient 45 air to the partly consumed products of combustion in order to continue the burning of the products as they pass through the secondary combustion chambers into the flues 9, and by the time they reach the chamber 50 40, they are practically consumed and very little, if any, smoke is produced. By making the secondary combustion chamber in sections, I find that the products of combustion are more readily consumed as the 55 metal of each section is brought to a high

heat and into intimate contact with the divided products of combustion, and I find that I can maintain a proper degree of heat in the several sections 17 by placing the front of each section in contact with the 70 boiler sections, and insulating the entire series of sections by the nonconducting covering. This arrangement also increases the life of the metal of the sections.

By making the secondary combustion 75 chamber in sections they can be kept in stock and assembled in the same manner as the boiler sections.

When it is desired to use a boiler having three sections, then only two of the secondary combustion chamber sections are necessary, but, when a greater number are required, the number of secondary combustion chambers is proportionately increased.

In Figs. 8 and 9, I have illustrated my 85 invention as applied to a vertical boiler, in which 3^a is the base. 2^a is the boiler section proper having a primary combustion chamber 14^a and 2^b is the top section, formed partly in the top section and partly in the 90 main section 2^a are flues 9^a and 10^a. 23^a are flues communicating with the main combustion chamber 14^a. In the present instance, there are two of these flues, one located at one side of the chamber 40^a having 95 the opening 42 leading to the chimney.

Located at each side of the boiler, as shown in Fig. 9 are the secondary combustion chambers 17^a built substantially in the same manner as the chamber 17 hereinbefore 100 described, so that the products of combustion pass from the primary combustion chamber 14^a through the flues 23^a and through the secondary combustion chambers 17^a, where additional air is supplied. The 105 consumed products of combustion pass through the flue 9^a into the central flue 10^a leading to the chamber 40^a. Bolts 28^a and 25^a are screwed directly into threaded openings in the sections of the boiler and hold 110 the secondary combustion chambers rigidly in position.

I claim:

1. The combination in a furnace having a primary combustion chamber, of a secondary combustion chamber located outside of the furnace and made in sections, each section being connected with the primary combustion chamber at the lower end and with the smoke flue at the upper end, and means 115 for admitting air to the secondary combustion chamber.
2. The combination of a furnace having a primary combustion chamber and a smoke flue above said chamber and having a back 125 wall with lower and upper flue passages therein; a series of independent secondary combustion chambers, the lower portion of each secondary chamber communicating with the primary combustion chamber 130

through the lower flue passages and the upper ends of the secondary chambers and with the smoke flues through the upper flue passages; and an inclosing casing made in 5 sections corresponding with the secondary combustion chambers.

3. The combination of a furnace having a primary combustion chamber and having a series of flues above the combustion chamber leading to a stack flue, said furnace consisting of a series of boiler sections arranged side by side and connected together, the flues being partially formed in the sections of the furnace; a series of secondary combustion chambers at the back of the furnace and communicating at the lower end with the primary combustion chamber and at the upper end with the flues; and sectional casings inclosing the secondary combustion chambers, the secondary combustion chambers being so proportioned and arranged that their joints are out of line with the joints of the sections of the boiler.
4. The combination of a furnace structure having a primary combustion chamber and having flues above said combustion

chamber, said furnace structure having lugs at the back; a secondary combustion chamber at the back of the furnace structure and recessed at the underside to receive the lugs and connected at the lower end with the primary combustion chamber and at the upper end with the flues; and means for holding the secondary combustion chamber to the furnace.

5. The combination of a furnace structure having a primary combustion chamber and flues above the chamber; a series of secondary combustion chambers made of cast metal and located at the back of the furnace structure, said combustion chamber casting being in contact with the back of the furnace structure and having flue openings at the bottom and at the top, the furnace structure having corresponding flue openings, one communicating with the combustion chamber and the other with the furnace flue; a non-conducting covering inclosing the exposed portions of said combustion chambers; and an inclosing casing 30 35 40 45 50 for the non-conducting material.

ABRAM C. MOTT, JR.
